UNITED STATES PATENT OFFICE

CARL O. B. LOFGREN, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT

LOCKING DEVICE

Application filed May 17, 1928. Serial No. 278,527.

This invention relates to locking devices for preventing the removal of certain electric fittings from the sockets in which they are threaded. In particular it has to do with 5 a lock for a fuse safety device.

It has been found that many persons, instead of replacing fuses which have blown out, insert a coin or other piece of conducting metal into the fuse socket in place of 10 the fuse, the coin bridging the space between the center and side contact pieces, thus completing the circuit. Then if a heavy current is sent through the circuit there is no fuse to blow out and the electrical devices in the 15 circuit are subjected to heavier current than their design contemplated.

Safety devices have been provided which, when inserted in a fuse socket, make it impossible to bridge the contacts by a coin and 20 difficult to insert anything except a fuse especially designed to fit the socket with the safety device in place.

The object of this invention is to provide a locking device for use with such safety 25 devices, or in similar fittings, to prevent their removal from the sockets in which they are threaded.

Another object is to provide a locking device for such purposes which shall be simple, 30 compact and economical.

A further object is to provide a locking device which will engage the socket wall securely regardless of slight irregularities in the contour of the wall.

35 One embodiment of the invention is described hereinafter and is illustrated in the accompanying drawing.

In the drawings—

Fig. 1 shows a sectional view of the safety 40 device, taken on line 1—1 of Figure 2 with certain portions below the section removed;

Fig. 2 is a section on line 2—2 of Fig. 1;

Fig. 3 is an exploded view of the safety device;

45 Fig. 4 is a section on line 4—4 of Fig. 1;

Fig. 5 shows in detail the toothed end of a locking dog;

Fig. 6 shows a spanner key for screwing the safety device in place.

50 The fuse safety device consists of a cir-

cular button 1 of insulating material having near the periphery on one face an annular wall 2 leaving a shoulder 3. The other face of this button is recessed to receive the locking mechanism. There is a main circular recess 4 leaving an annular rim 5 which has 55 two apertures 6, 7 equidistant on the periphery. In register with these apertures and on opposite sides of the center are divergent transverse shallow recesses 8, 9, these recesses 60 having their inner side walls parallel each to each, and their outer side walls divergent from the inner walls. At the inner ends of these recesses are countersunk portions 10, 11. Extending between recesses 8, 9 at one 65 side of the button is a crescent shaped recess 12 of less depth than the recesses 8, 9, the three recesses leaving a central transverse boss 13. Through the center of the button is a circular opening 14. 70

For threading the device into the fuse socket, there is provided a screw thread shell 15 which surrounds the button 1, one end being flanged to overlie the rim 5 and the other end being turned in over the shoulder 3 in 75 any known manner. This shell is slotted opposite the apertures 6 and 7 and has in-turned lugs, shown at 17, 18 in Figure 1, which extend into recesses in the rim 5 to prevent rotation of the shell about the button. 80

The locking mechanism consists of two dogs 19, 20 of identical shape, stamped from thin metal. These dogs have off-set ends 21, 22 which, when the dogs are placed in the recesses 8, 9, extend into the counter sunk 85 portions 10, 11. These portions are of such size as to permit limited longitudinal movement of the dogs and so afford a loose pivoting of the dogs on the button. The other ends of the dogs are serrated and extend 90 through the apertures 6, 7 and the slots in the shell 15, the serrated or toothed ends lying adjacent the periphery of the device.

Fig. 5 best shows the outer toothed end. It is to be noted that each tooth presents a 95 sloping face in the direction of desired rotation, indicated by the arrow, and a sharply inclined face in the reverse direction. By reason of the eccentric position of the pivot, the toothed end, in swinging to the dotted 100

line position, moves from beyond the periphery of the shell 15 to a position adjacent the periphery. Or, in other words, when the dogs lie against the inner walls of their recesses, the toothed ends extend but slightly beyond the shell 15 but when swung over to engage the divergent outer walls of the recesses, the toothed ends protrude a substantial amount beyond the periphery of shell 15. The reason for this is, of course, that the toothed ends swing on an arc the center of which is not at the center of the button.

Each dog has a hole through it to receive an offset end of the spring 23 which is curved to lie in the recess 12 around the curved end of the boss 13. The tendency of the ends of the springs to separate causes the dogs to be pushed against the divergent sides of their recesses, the ends 21, 22 pivoting in the recesses, 10, 11, thus extending the toothed portions 24, 25 beyond the periphery of shell 15. It is noted that the direction of turning about the pivots, caused by the spring is the same as the desired rotation of the body about its center. The spring tends also to push the dogs outward to the limit of extension permitted by the loose pivoting in recesses 10, 11. This slight permitted movement of the pivot compensates for any irregularities in the periphery of the shell 15 and particularly for the fact that the socket shell is shaped to provide threads, and all portions of its periphery in any plane are not equidistant from the center.

To secure the mechanism in position, there is a disc 26 of fibrous material which fits within the rim 5 and rests on the boss 13 and is flush with the top of rim. Another larger disc 27 of fibrous material rests on the flange 16 of shell 15 which overlies the rim 5. A third, small disc 28 which may be of metal, rests on the disc 27. A rivet 29 having a closed flanged end 30 extends from the under side of the button through the three discs and has its other end pressed over upon the disc 28 thus binding all the parts securely together.

The button 1 is most easily made by molding. The metal parts consisting of the dogs, the spring, the rivet and the screw shell are of simple shape and the cost of making them is slight. The discs are cut from sheet material. It is seen therefore that the device accomplishes the object of simplicity and economy in the matter of manufacture. Moreover, it is compact since all the parts are flat and fit closely together.

The safety device is screwed into the usual fuse socket by means of a spanner key 36 inserted in spaced recesses 34, the dogs offering no resistance to turning since the sloping flanks of the teeth first meet the socket wall and the dogs are swung about their pivots against the inner walls of their recesses in

which position the toothed ends are close to the periphery of the shell. If necessary, due to irregularity in the socket the dogs move inwardly in the recesses 10, 11 against the resilient effort of the spring. The fuse is then screwed into place with its contact shell lying outside the annular insulating wall 2 and its center contact engaging the head 30 of rivet 29. The other end of the rivet engages the center contact of the socket so that the rivet serves as a conductor between the fuse and socket contacts.

If the fuse blows out, it may be removed and another one inserted. A coin or other article can not be used because of the wall 2. By properly relating the extent of wall 2 from the button 1 and the extent of the fuse shell and fuse center contact from the body of the fuse, the use of any but a proper size of fuse may be prevented.

The safety device cannot be removed because if reverse rotation is attempted the slightly protruding toothed ends 24, 25, with the sharply inclined face presented in the attempted direction of rotation, at once engage the walls of the socket shell and tend to swing the dogs about the pivoting ends 21, 22 into position in which they extend even more beyond the shell 15; that is, they are swung against the divergent walls of their recesses. Therefore in addition to affording frictional resistance to turning, the toothed ends bite into the relatively soft metal of the shell and afford a positive lock.

Modifications of this preferred embodiment will doubtless occur to others in the exercise of their skill in the art or of their inventive faculties. The invention is not limited to the embodiment shown but comprehends all such modifications as fall within the scope of the following claims.

I claim—

1. In a safety device for a fuse, a button, transverse, divergent, non-radial recesses in one face of the button, said recesses extending to the periphery at spaced points thereabout, dogs pivoted in said recesses and having toothed ends adjacent the periphery, and a spring means engaging each dog and urging it about its pivot in the direction of desired rotation of the device.

2. In a safety device for a fuse, a button, transverse, divergent, non-radial recesses in one face of the button, said recesses extending to the periphery at spaced points thereabout, dogs pivoted in said recesses and having toothed ends adjacent the periphery, spring means engaging each dog and urging it about its pivot in the direction of desired rotation of the device and a cap member on said body for holding said dogs and spring means in position.

3. In a safety device for a fuse, a button, transverse, divergent, non-radial recesses in one face of the button, said recesses extend-

ing to the periphery at spaced points thereabout, dogs pivoted in said recesses and having toothed ends adjacent the periphery, spring means engaging each dog and urging it about its pivot in the direction of desired rotation of the device and a cap member on said body for holding said dogs and spring means in position, a conducting member extending through said body and said cap member, securing said cap on the body and affording center contacts on each side of the body.

4. In a safety device for a fuse, a body portion having a peripheral rim on one side thereof, transverse, divergent, non-radial recesses in one face of the body portion, said recesses extending to the periphery at spaced points thereabout, said rim being apertured at said points, dogs pivoted in said recesses, and having toothed ends adjacent the periphery, a spring means engaging each dog and urging it about its pivot in the direction of desired rotation of the device, and a cap member on said body for holding said dogs and spring means in position.

5. A safety device for a fuse comprising a button having socket engaging means thereon, an annular wall on one side thereof spaced from the periphery, a peripheral rim on the other side, said other side having two divergent transverse recesses on opposite sides of the center and extending in opposite directions, with a curved connecting recess of less depth, said rim being apertured in register with said recesses, dogs pivoted in each transverse recess and extending adjacent the periphery of said body portion, the ends of the dogs being toothed, a curved spring lying in the connecting recess and engaging both dogs to urge them about their pivots in the direction of desired rotation of the body, a disc within the rim and resting on said spring and dogs, a cap on said rim and a rivet extending through the body and engaging said cap member, said rivet affording center contacts on each side of the body.

6. A locking mechanism for preventing reverse rotation of a circular body having a screw shell for threading into a socket, comprising a dog having a toothed end extending through a slot in the screw shell and adapted to bite on reverse rotation, said dog being pivotally mounted at an off-center part of the body and having limited freedom of non-pivotal movement whereby the position of its toothed end may vary, together with resilient means urging the toothed end of the dog outwardly and about its pivot in the direction of desired rotation.

60 In testimony whereof I have signed my name to this specification.

CARL O. B. LOFGREN.
